UNITED STATES PATENT OFFICE

GEORGE HERBERT CONOR, OF BUENOS AIRES, ARGENTINA

AUTOMATIC LOADING TRANSPORTER

Application filed April 11, 1927, Serial No. 182,752, and in Great Britain April 6, 1927.

The present invention relates to an automatic unloading or dumping conveyor apparatus and has for its object to provide such an apparatus adapted for use for the formation of mows in the fields, and generally for all those uses in which it is required to heap up a camp or to load vehicles with cereals in spikes or in grain, or any other sorts of material, whether consisting of liquids, powder, grain or stone.

The invention has more particularly for its object to provide an automatic dumping conveyor apparatus in which a bucket is pivoted to a frame which is provided with rollers for running along a rail, the bucket being pivoted to the frame above the center of gravity of said bucket so that it will normally remain with its open top turned upwardly, means such as a rope or cable being provided secured to the leading end of said bucket and to a fixed point in such manner that when said bucket in traveling along the rail, reaches the desired dumping point, said means will automatically overturn said bucket, dumping its contents.

A preferred embodiment of my invention will now be described in the drawings for illustrative purposes.

In the drawings Fig. 1 shows a perspective view of an automatic unloading conveyor constructed in accordance with the invention.

Fig. 2 is a lateral elevation of the same conveyor bucket, also shown in dotted lines in its dumping or reversed position.

Fig. 3 is a front projection of the bucket in its loading or upright position.

Figs. 4 and 5 show schematically how the bucket is dumped.

In the illustrative embodiment as shown, the overturnable bucket 1 is pivoted at the point 2 in the lateral arms 3 of a suitable frame. Several points 2 may be provided, herein three, that pivotal point being selected which is best suited to the capacity and form of the bucket. All three of said pivotal points are situated above the center of gravity of the bucket so that the bucket will normally always be maintained with its open top turned upwardly by gravity. The

bucket can be turned upon its pivots to dump its contents.

The frame in which the bucket is pivotally supported consists of a pair of cross bars 5, one at each end, and downwardly curved side members 3 connecting the endes of said cross bars. A roller or sheave 6, suitably mounted on each of said cross bars, runs upon a rail 7 in fore and aft spaced relation, and a traction member such as cable 8 is secured to the leading end of said frame to enable said bucket to be conveyed from its loading point to the point where its contents is to be dumped. The bucket could also be pivoted in a wagonet running on rails in which case wheels would be substituted for the sheaves 6 in the ends of the arms 3, and these would remain in an inverted position with relation to the ones represented in the drawings. The bucket may suspend in any other suitable manner, as will be readily understood by those skilled in the art.

Means are herein provided for automatically dumping the contents of the bucket when it reaches the desired dumping point. Herein said means may comprise a cable or trip rope 4 secured at one end to the leading end of said bucket and the other end to a fixed point or anchorage selected in such manner that when in its movement from loading to dumping position the bucket reaches the desired dumping point, said cable will have become taut thus overturning the bucket as shown schematically in Figs. 4 and 5 and dumping its contents.

I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

I claim:

1. Automatic dumping conveyor apparatus comprising in combination, a trackway, an anchorage therebeneath, a carriage adapted to run on said trackway, said carriage comprising a cross bar at each end and a U-shaped

longitudinal bar at each side connecting the ends of said cross bars, a roller supporting each of said cross bars on said trackway, selectable pivot bearings in the lowest portion 5 of said side bars, a bucket pivoted above its center of gravity upon said bearings, said bucket having flat sides parallel to said cross bars, and a trip rope connected to one end of said bucket and to said anchorage and 10 adapted to invert said bucket at a predetermined point of travel.

2. Automatic dumping conveyor apparatus comprising in combination, a trackway, an anchorage therebeneath, a carriage adapted to 15 run on said trackway, said carriage comprising a pair of spaced cross bars each carrying a roller to run on said trackway and a pair of U-shaped longitudinal side bars connecting the ends thereof, selectable pivot bearings in 20 the lowest portion of said side bars, a bucket pivoted above its center of gravity upon said bearings, said bucket comprising flat parallel sides, a short horizontal bottom, one rounded end and one inclined end, both directed away 25 from said bottom, and a trip rope secured to the inclined end of said bucket and to said anchorage, adapted to dump said bucket at a predetermined point along said track.

3. Automatic dumping conveyor apparatus 30 comprising in combination, a trackway, an anchorage, a carriage adapted to run on said trackway, said carriage comprising a pair of fore and aft spaced cross bars, each carrying a roller to run on said trackway, a pair of side 35 bars connecting the ends of said cross bars, pivot bearings in the lowest portions of said side bars, a bucket pivoted above its center of gravity upon said bearings, said bucket comprising parallel sides, an inclined leading end 40 for said bucket, and a trip rope secured to said inclined end and to said anchorage, adapted to effect the tilting of said bucket toward said inclined end at a predetermined point along said track.

45 In testimony whereof, I have signed my name to this specification.

GEORGE HERBERT CONOR.
